UNITED STATES PATENT OFFICE.

AMOS M. ULMER AND FRANK FOWLER, OF PHILADELPHIA, PA.

BRAKING MECHANISM FOR MACHINERY.

SPECIFICATION forming part of Letters Patent No. 267,953, dated November 21, 1882.
Application filed September 29, 1882. (No model.)

To all whom it may concern:

Be it known that we, AMOS M. ULMER and FRANK FOWLER, citizens of the United States, and residents of Philadelphia, Pennsylvania, 5 have invented certain Improvements in Braking Mechanism for Machinery, of which the following is a specification.

Our invention relates to certain improvements in mechanism whereby the speed of a 10 rotating and longitudinally-traversing wheel is gradually slackened prior to the stoppage of its movement, the invention being of especial importance in cases where the movement of the wheel is checked by contact of a portion of said wheel with a fixed stop, the object 15 of our invention being to prevent the severe shock and recoil due to the sudden stoppage of the wheel when it is rotating at full speed.

In the accompanying drawings, Figure 1 is 20 a view showing our improvement applied to the feed-roll-operating mechanism of a spinning-mule; Fig. 2, a sectional view of the device forming the subject of our invention, said view being drawn to a larger scale than Fig. 25 1; and Fig. 3, a perspective view of the device.

Before describing our invention, we will first give a general description of that part of a spinning-mule which is shown in Fig. 1, in order that a better understanding may be had of 30 the nature and object of our improvement.

A represent parts of the frame of the mule, in which are formed bearings for the main driving-shaft B, and for one of the rolls D, whereby the slubbing is fed into the machine. This 35 feed-roll must have an intermittent movement imparted to it—that is to say, it must feed the slubbing forward during the first part of the movement of the carriage, and must then be held stationary while the drawing, spinning, 40 and winding operations are being performed. These movements of the feed-roll are effected in the following manner:

On the roll D is a loose sleeve, E, which is 45 driven in any suitable manner from the main shaft. On this sleeve is a clutch, a, adapted to engage with a clutch, b, secured to the feed-roll, on which is a similar clutch, d, adapted to engage with a clutch, e, on a pinion, F, which can turn loosely on the roll D. The pinion F 50 gears into a spur-wheel, G, the hub of which is threaded internally, and is adapted to a

screw-spindle, J, projecting from the frame A. The wheel G is secured to or forms part of a drum, M, to which is attached one end of a cord, f, said cord passing over a pulley, g, and having at the opposite end a weight, h. On one side of the wheel G is a lug, m, and on the opposite side a lug, n, and on the frame A is a projecting arm, p, as shown in Fig. 1.

To a suitable bearing on the frame is pivoted 60 a lever, N, which serves as a catch to hold the clutches b and d in gear with the clutches a and e, the clutches being thrown out of gear by suitable mechanism when released from the control of the lever.

When the feed-roll D is stationary the lug 65 m on the wheel G is in contact with the projecting arm p, the cord f is unwound from the drum M, and the clutches are out of gear. As soon as the clutches are thrown into gear and 70 locked by the lever N the wheel G is rotated by the pinion F, so as to traverse on the screw-spindle J in the direction of the arrow 1, Fig. 1, thus winding up the cord on the drum M. The traversing movement continues until the 75 lug n on the wheel comes into contact with a finger, t, on the lever N, when said lever will be operated so as to release the clutches, 80 whereupon the rotation of the feed-roll D will cease, the finger t being adjustable on the lever, so that any desired extent of movement of the feed-roll may be permitted before the 85 operation of the lever and the stoppage of said movement. The pinion F being now free from the roll, the weight on the cord f will cause the same to be unwound from the drum M, thereby turning the wheel G and causing 90 it to traverse on the screw-spindle in the direction of the arrow 2, this movement continuing until the lug m comes into contact with 95 the arm p. The contact of the lug m with the arm while the wheel G is rapidly rotating causes such a shock that injury to the machinery is the frequent result, the commonest accident being the breaking off of the teeth 100 of the wheel G and pinion F, so that frequent stoppages of the mule are required for the repair or replacing of these parts. The recoil of the wheel on the contact of the lug m and arm p is another objection, as it causes the wheel G on its next operation to start in advance of the proper position, so that the

length of slubbing fed in is shorter than it should be, and imperfect yarn is the result. It is these objections which it is the aim of our invention to overcome, and we attain the 5 desired result by gradually retarding the rotation of the wheel G as it approaches the limit of its movement in the direction of the arrow 2. This is effected by means of a friction-block, w, the stem y of which is adapted 10 to slide in a recessed bearing, T, on the frame, a spring, x, tending to force the block w outward, and a transverse pin, s, in the bearing being adapted to a recess in the stem, y, so as to limit the extent of said outward movement. 15 As the wheel G approaches the limit of its movement in the direction of the arrow 2 the block w will come into frictional contact with the face of the wheel, and as the latter continues its movement the block will be forced 20 inward, and the spring x will be compressed so as to gradually increase the friction, and thus gradually retard the speed of the wheel, so that when the lug m comes into contact with the arm p the speed will have been so far 25 reduced that no severe shock will result and no recoil will take place.

Our invention is applicable to other machines than spinning-mules. For instance, it may be used in connection with the feed-rolls of different machines, or with the feeding devices 30 of wood or metal working machines, or with the rotating and traversing plunger of a press, and in some of these cases the brake alone

may be relied upon to stop the movement of the wheel, no fixed stop being used. It is, 35 however, of special advantage in cases where such a fixed stop is employed.

We claim as our invention—

1. The combination of the rotating and traversing wheel G with a brake, w, adapted 40 to yield in the direction of the traverse of the wheel, whereby a gradually-increasing pressure is brought to bear on the wheel as it nears the end of its movement, as set forth.
2. The combination of the rotating and 45 traversing wheel G, having a lug, m, the fixed stop p, and the brake w, adapted to yield in the direction of the traverse of the wheel, as set forth.
3. The combination of the spur-wheel G, its 50 drum M and lug m, the stop p, the screw-spindle J, the pinion F, and the brake w, as set forth.

4. The combination of the rotating and traversing wheel G, the bearing T, the brake-block w, having a stem adapted to slide in the 55 bearing, and a spring, x, as set forth.

In testimony whereof we have signed our names to this specification in the presence of two subscribing witnesses.

AMOS M. ULMER.
FRANK FOWLER.
